UNITED STATES PATENT OFFICE.

EDWIN R. CAHOONE, OF NEWARK, NEW JERSEY.

HEATING-STOVE.

SPECIFICATION forming part of Letters Patent No. 698,803, dated April 29, 1902.

Application filed July 11, 1901. Serial No. 67,888. (No model.)

To all whom it may concern:

Be it known that I, EDWIN R. CAHOONE, a citizen of the United States, residing at Newark, in the county of Essex and State of New

5 Jersey, have invented certain new and useful Improvements in Heating-Stoves; and I do declare the following to be a full, clear, and exact description of the invention, such as will enable others skilled in the art to which it applies to make and use the same, reference being had to the accompanying drawings, and to the figures of reference marked thereon, which form a part of this specification.

This invention relates to improvements in 15 heating-stoves designed, primarily, for burning bituminous coal. In stoves of this general character it has been customary to take the air from the atmosphere direct to a chamber, where it is heated, and from this chamber 20 deliver it direct to the fuel; but this means of heating air to promote combustion has many disadvantages, for the obvious reason that the air is not sufficiently warm to mix and ignite the gases. Hence a large percentage 25 of the latter is carried off in smoke. It is therefore the purpose and object of my present improvements to provide means for taking the heated air surrounding the stove into a chamber, where it is heated to a higher degree 30 and from whence it is directed through ducts to an air-heating chamber in proximity to the fire-pot.

The invention also contemplates improvements in the specific manner of introducing 35 heated air to various parts in the fire-pot.

Many other objects and advantages will become apparent in the description to follow and be particularly pointed out in the claims.

In the drawings forming a part of this specification, Figure 1 is a perspective view of my improved stove. Fig. 2 is a vertical section of the same. Fig. 3 is a detail perspective view of the casting forming part of the auxiliary air-heating chambers and the ducts. 45 Fig. 4 is a detail vertical section similar to Fig. 2, but taken through an adjoining auxiliary air-heating chamber. Fig. 5 is a cross-section on the line A A of Fig. 2. Fig. 6 is a bottom plan view of the stove-top. Fig. 7 is 50 a view in elevation of a modification, showing parts in section. Fig. 8 is a similar view of a still further modification. Fig. 9 is a de-

tail cross-section of the same. Fig. 10 is a detail section showing a single air-heating chamber to receive the ascending air, the 55 tubes being omitted.

In the drawings, 1 indicates a base; 2, a casing; 3, a fire-pot; 4, a magazine, and 5 a top.

An air-heating chamber 6 is suitably supported and provided with three series of air-exits 9, 10, and 11. In the latter fit pendent bars 12, which form the lower part of the fire-pot. The chamber 6 is preferably made in sections and is located in proximity to the 65 fire, so as to be thoroughly heated thereby. At the same time the walls of the chamber are not seriously affected by the action of the intense heat, this being by reason of the constant supply of air being delivered thereto. 70

The top 5 is composed of a supporting-section 15, a plate 16, and a cover 17. The cover 17 has formed on its lower side a series of depending partitions 18, forming what I shall term "two sets of auxiliary individual air-heating chambers." One set of auxiliary chambers 20 is supplied with heated air through openings 22 in the supporting-section 15. (See Fig. 4.) The air thus taken is that which surrounds the stove and which always 80 has a natural tendency to ascend, and while ascending it becomes warm by the time said openings are reached. The air thus introduced to these chambers becomes thoroughly heated therein, whereupon it is delivered to 85 the fuel through tubes 20^a under the influence of the draft. The other set of auxiliary air-heating chambers 23 is supplied with air from the perforations 23^a and after being somewhat heated is delivered through ducts 90 24, formed adjacent the inside of the casing 2, to the air-heating chamber 6. The gases passing to the exit-flue through the space 25 between the magazine 4 and the casing 2 gradually and thoroughly heat the air before it is 95 delivered to the fuel.

The operation is substantially as follows: Fire being started, the air around the stove is heated, and as it ascends it contacts with the overhanging deflector-like portion 15^a of the 100 supporting-ring 15 to the auxiliary air-heating chambers 20, where, by reason of its constant contact with the walls thereof, it is further heated and in this condition is delivered

downwardly to the fuel through the tubes 20^a. Likewise the air delivered through the perforations 23^a contacts with the walls of the chambers and is warmed, it being borne in 5 mind that air so taken has not been previously subjected to heat. After being somewhat heated in the chambers 23 the air passes through the perforations 22^a to the ducts and thence to the air-heating chamber 6. Heated 10 air is drawn direct through the fuel-bed at different angles, under the influence of the draft, through the openings 9, 10, and 11. The openings 11 are of such size as to permit the escape of air when the pendent bars are in 15 position. The ducts consist of depressed plates fitted to correspond to the contour of the stove-casing, the latter forming one of the walls of said ducts. Moreover, the ducts in the rear are of single formation, while those 20 toward the front are forked, this being for the purpose of equalizing the heating-surface. While this construction is preferred, it is apparent tubes or ducts of any well-known form may be employed, and I desire 25 to reserve this right. Gathering, as it were, the ascending radiant heat, superheating, and then delivering it through the fuel prevents the generation or escape of smoke gases which have been heretofore almost uncon- 30 trollable. Experience has demonstrated that soft coal can be burned without smoke or soot for heating purposes only when the generated gases are met and mixed by air heated to such degree as will effectually cause the 35 molecules of gas to be agitated to create certain resistances, and this I bring about by the location and arrangement of the air-introducing means. Experience has also proved that the air which is delivered through the 40 fuel from above while being drawn into the heating-chambers direct from the atmosphere is heated by the time the incandescent mass is reached to approximately the same temperature as the air delivered from the air- 45 heating chamber surrounding the fire-pot.

A damper 35 is employed to simultaneously regulate the admission of air to the tubes and ducts, so that the fire may be at all times under control. 50 A drum 30 may surround the casing, forming a space 31 between the two, so that the air entering the chamber 20 can be heated to a degree of surety, and in connection with this drum the escape-flue 32 is constructed in 55 such manner as to radiate the heat and to more thoroughly utilize the same for heating purposes. The exit-flue 32 is connected at 36 by an auxiliary flue 37, which is bent around toward the front and then directed down and 60 toward the rear, where it passes out through the drum and again joins the exit-flue at 38. Between the points 36 and 38 is a damper 39, so that the draft may be either direct or tortuous. It is obvious that while the escaping 65 gases are directed through the auxiliary flue that heat therein is maintained for a longer period. Consequently the surrounding air is

heated, and the full effect of the heat is obtained.

In the disclosure shown in Fig. 7 the same 70 arrangement of air-heating chambers and the internal structure is substantially the same as illustrated in the preceding figures; but in addition thereto I have added a modification of the means for maintaining the escap- 75 ing gases within the stove for a greater period than usual, thereby utilizing all the heat. In said figure, 50 represents a series of flues connecting the space 31 at the top and a cham- 80 ber 51 below the grate, said chamber commun- 85 icating with a flue 52, which is connected to the exit-flue 53 by a pipe 54. In the exit-flue 53 is a damper 55, so that if it be desired to make the gases pass through the flues 50 be- 90 fore escaping to the atmosphere the exit-flue 53 will be closed. On the other hand, if it be de- 95 sired to take the gases from the stove direct said damper will be opened. In using such a construction it is preferred to utilize a drum having the usual escape-flues 58. However, the drum may be dispensed with, and I re- 100 serve this right.

In Figs. 8 and 9 I have illustrated a series 105 of flues running up from the bottom of the stove to take in the air and heat it before be- 110 ing delivered to the auxiliary heaters. How- 115 ever, in all other respects the construction is substantially the same as that hereinbefore described.

In Fig. 10 I have shown a single chamber 100 75 to receive the ascending heated air and have omitted the depending tubes 20^a, open- 105 110 ings 76 being provided for introducing air to the fuel.

It is obvious that while I have shown the 105 auxiliary heating-chambers applied to a down- 110 draft-stove they are equally applicable to an updraft structure. Moreover, in the general description and claims I have used the word 115 "chambers" to specify the structure; but one chamber under certain circumstances is used advantageously, and I desire to state that where this term is used its meaning im- 120 plies a single auxiliary chamber. I there- 125 fore desire to reserve the right to the use of either a chamber or chambers.

Having thus fully described my invention, what I claim as new, and desire to secure by Letters Patent, is—

1. A downdraft-stove comprising a casing, 120 a fire-pot, an air-heating chamber or cham- 125 bers arranged at the top of the stove to receive the ascending heated air surrounding the stove, means for directing the air to said chamber or chambers, and means commun- 130 icating with said chambers for delivering said heated air downwardly in individual currents to the fuel from which the gases are generated, said heated air being drawn through the fuel under the influence of the draft.

2. A stove comprising a casing, a fire-pot, an air-heating chamber in proximity to the fire- 130 pot, auxiliary air-heating chambers, means connecting the chamber in proximity to the

fire-pot and the auxiliary air-heating chambers, a second set of auxiliary chambers, and tubes depending therefrom toward the bed of the fuel to direct currents of heated air there-through.

5 3. A stove comprising a casing, a fire-pot, an air-heating chamber in proximity to said fire-pot, auxiliary air-heating chambers, a deflector adapted to deflect the ascending heated air surrounding the stove to said chambers and toward the fuel to direct currents of heated air through the fuel-bed.

10 4. A stove comprising a casing, a fire-pot, a space being formed between said casing and fire-pot, a flue communicating with the aforesaid space, an air-heating chamber in proximity to said fire-pot, auxiliary air-heating chambers, ducts connecting said latter air-heating chambers and the air-heating chamber in proximity to the fire-pot, said ducts being located between the casing and the fire-pot in the path of the gases escaping to the exit-flue.

15 5. A stove comprising a casing, a fire-pot, a flue, an air-heating chamber arranged to deliver currents of heated air to the fuel, two sets of auxiliary air-heating chambers, means for supplying one set of auxiliary air-heating chambers with the ascending heated air which surrounds the stove, tubes depending from said chambers to deliver currents of air through the fuel from the top, the second set of auxiliary chambers being supplied with air from the top, and ducts connecting said latter auxiliary air-heating chambers with the said air-heating chamber which surrounds the fire-pot.

20 6. A heating-stove comprising a casing, a fire-pot, a flue, a perforated air-heating chamber in proximity to and surrounding the fire-pot, two sets of auxiliary air-heating chambers in the stove-top, deflectors arranged to deliver air to one set of said chambers, means connected to said chamber for delivering heated-air currents downwardly through the fuel, the second set of auxiliary chambers being supplied with air from the top, and ducts connecting said latter chambers with the air-heating chamber located in proximity to the fire-pot.

25 7. A stove, comprising a casing, a fire-pot, a main flue, air-heating chambers arranged to receive the ascending heat surrounding the stove, a space being formed between the fire-pot and drum, a drum, an auxiliary flue in said space, said flue being connected at both ends with the main exit-flue, and a damper adapted to direct the escaping gases either to the main flue or the auxiliary flue.

30 8. A downdraft-stove, a drum comprising a casing, a fire-pot, a main exit-flue, air-heating chamber or chambers arranged to receive the ascending heat surrounding the stove, a space being formed between the casing and the drum, an auxiliary flue in said space one end of said flue being positioned to receive the escaping products of combustion and its

opposite end in communication with the main exit-flue, and a damper adapted to direct the escaping gases either to the main flue or the auxiliary flue.

7c 9. A downdraft-stove comprising a casing, a fire-pot, air-heating chamber or chambers arranged at or near the top of the stove to receive the ascending heated air surrounding the stove, means for deflecting said ascending heated air to said chamber or chambers, and tubes extending from said chamber or chambers for delivering heated air downwardly in individual currents to the fuel, from which the gases are generated, said heated air being drawn through the fuel under the influence of the draft.

75 10. A downdraft-stove comprising a casing, a fire-pot, air-heating chamber or chambers arranged at the top of the stove to receive the ascending heated air surrounding the stove, an air-heating chamber in proximity to the fire-pot, means of communication between said chamber or chambers and the air-heating chamber surrounding said fire-pot, whereby currents of heated air are delivered to the fuel, said currents of air being drawn through the bed of fuel under the influence of the draft.

95

100 11. In a downdraft-stove, the combination with a casing, a fire-pot, an exit-flue, air-heating chamber or chambers arranged at or near the top of the stove to receive the ascending heated air which surrounds the stove, means for deflecting the said heated air to the chambers, and tubes extending from said chamber or chambers for delivering heated air to the fuel, said heated air being drawn through the fuel under the influence of the draft.

105

110 12. In a downdraft-stove, the combination with a casing, a fire-pot, air-heating chambers arranged to receive the ascending heat surrounding the stove, an air-heating chamber surrounding the fire-pot, means connecting the chambers which receive the ascending heated air and the chamber which surrounds the fire-pot, whereby the ascending heat is preheated and delivered to the fuel, said air being drawn through the fuel under the influence of the draft, a drum, and an exit-flue located between the casing, and drum, whereby the ascending air is heated.

115

120 13. In a downdraft-stove, the combination with a casing, a fire-pot, an exit-flue, air-heating chambers adapted to receive the ascending heated air which surrounds the stove, said air being delivered to the fuel through openings in the chambers, and drawn through the fuel-bed under the influence of the draft, a drum, a chamber, flues connecting said chamber, and a space between the fire-pot and casing, and means for directing the escaping gases through the said flues and chamber, or direct through the exit-flue.

125

130 14. In a stove, the combination with a casing, a fire-pot, an exit-flue, an air-heating chamber having openings surrounding the fire-pot and adapted to deliver air to the fuel, means

for deflecting the ascending heated air which surrounds the stove to the air-heating chamber in the fire-pot, means for delivering heated air to the fuel from the top, and a series of tubes for delivering a plurality of air-currents to the fuel intermediate the air-currents delivered from the top and the currents of air delivered from the air-heating chamber in the fire-pot.

- 10 15. In a downdraft-stove, the combination with a casing, a fire-pot, an exit-flue, an air-heating chamber having openings surrounding the fire-pot, and adapted to deliver air to the fuel, means for deflecting the ascending heated air which surrounds the stove to the air-heating chamber in the fire-pot, means for delivering heated air to the fuel from the top, and a series of tubes for delivering a plurality of air-currents to the fuel intermediate 15

20 the air-currents delivered from the top, and the currents of air delivered from the air-heating chamber in the fire-pot, all of said currents of air being drawn through the fuel under the influence of the draft.

25 16. In a downdraft-stove, the combination with a casing, a fire-pot, an exit-flue, an air-heating chamber arranged to deliver currents of heated air to the fuel, two sets of auxiliary air-heating chambers, means for supplying 30 one set of auxiliary air-heating chambers with heated air, tubes depending from said chambers to deliver currents of air to the fuel, the second set of auxiliary chambers communicating direct with the atmosphere, ducts connecting said second set of auxiliary chambers with the first-named air-heating chamber, the two sets of currents of air delivered to the fuel from the latter chamber, and from 35 the tubes, being drawn through the fuel under the influence of the draft.

40 17. In a downdraft-stove the combination with a casing, a fire-pot, an exit-flue, a plurality of air-heating chambers arranged at or near the top of the stove to receive the ascending heated air which surrounds the stove, means arranged adjacent the fire-pot for pre-heating the air and delivering said air to the fuel and means communicating with said 45 chambers and the means for preheating the air, the heated air being drawn through the fuel under the influence of the draft.

50 18. In a downdraft-stove, comprising a fire-pot, an air-heating chamber from which heated air is delivered to the fuel, auxiliary air-heating chambers, means connecting the air-heating chamber and the auxiliary air-heating chambers, a second set of auxiliary chambers, having openings through which currents of heated air are directed to the fuel, said latter 55 currents of heated air and the air delivered to the fuel from the first-named air-heating chamber being drawn through the fuel under the influence of the draft.

60

19. In a downdraft-stove, the combination with a casing a fire-pot, auxiliary air-heating 65 chambers at or near the top of the stove, means for gathering and deflecting into the auxiliary chambers the ascending heated air which surrounds the stove, an air-heating chamber having a series of openings to deliver heated-air currents to the fuel, means 70 connecting the latter air-heating chamber and the auxiliary air-heating chambers, the air-currents from the air-heating chamber being drawn through the fuel under the influence 75 of the draft.

20. In a downdraft-stove, the combination with a casing a fire-pot, an exit-flue, auxiliary air-heating chambers at or near the top of the stove, an air-heating chamber surrounding the fire-pot and having a series of exit-openings to direct currents of air to the fuel, and ducts connecting the auxiliary air-heating chambers and the air-heating chamber which surrounds the fire-pot, said ducts being located to be heated by the heat in the fire-pot, the heated-air currents delivered to the fuel being drawn through the fuel-bed under the influence of the draft. 80 85

21. In a downdraft-stove, the combination 90
with a casing, a fire-pot, an exit-flue, air-heating
chambers arranged to receive the ascending
heated air surrounding the stove, means
communicating with the said air-heating 95
chambers for delivering heated-air currents
to the fuel, and a series of tubes communic-
ating with the atmosphere for delivering a
plurality of air-currents to the fuel independ-
ent of the heated-air currents delivered from
the air-heating chambers, all of said currents 100
of air being drawn through the fuel under the
influence of the draft.

22. In a downdraft-stove, the combination with a casing, a fire-pot, a space being formed between the casing and the fire-pot, an exit-flue communicating with said space, a drum spaced from the casing, tubes entering the fire-pot and communicating with the atmosphere, the air entering said tubes being heated by the ascending heated air in the space formed between the drum and the casing, and the space between the fire-pot, and casing, air-heating chambers arranged to receive the ascending heated air which surrounds the stove means communicating with said air-heating chambers for delivering currents of preheated air to the fuel, all of the aforesaid currents of heated air being drawn through the fuel under the influence of the draft. 105 110 115

In testimony whereof I affix my signature **120** in presence of two witnesses.
